(57) **CLAIM**

The ornamental design for a point of sale device as shown and described.

DESCRIPTION

FIG. 1 is a perspective view of a new and ornamental design for a point of sale device;

FIG. 2 is a front elevation view of the point of sale device shown in FIG. 1;

FIG. 3 is a rear elevation view of the point of sale device shown in FIG. 1;

FIG. 4 is a left side elevation view of the point of sale device shown in FIG. 1;

FIG. 5 is a right side elevation view of the point of sale device shown in FIG. 1;

FIG. 6 is a top plan view of the point of sale device shown in FIG. 1;

FIG. 7 is a bottom plan view of the point of sale device shown in FIG. 1;

FIG. 8 is a perspective view of a new and ornamental design for a point of sale device;

FIG. 9 is a front elevation view of the point of sale device shown in FIG. 8;

FIG. 10 is a rear elevation view of the point of sale device shown in FIG. 8;

FIG. 11 is a left side elevation view of the point of sale device shown in FIG. 8;

FIG. 12 is a right side elevation view of the point of sale device shown in FIG. 8;

FIG. 13 is a top plan view of the point of sale device shown in FIG. 8; and,

FIG. 14 is a bottom plan view of the point of sale device shown in FIG. 8.

The dash-dash broken lines in the various views, for example in FIGS. 1-14, represent components and design features of the point of sale device that form no part of the claim. The dash-dot broken lines in the various views, for
